MAGNETIC DESK NAME PLATE

Filed March 26, 1947

Jay J. Hatfield
INVENTOR

UNITED STATES PATENT OFFICE

155,421

DESIGN FOR A MAGNETIC DESK NAME PLATE

Jay J. Hatfield, Asbury Park, N. J.

Application March 26, 1947, Serial No. 138,325

Term of patent 3½ years

(Cl. D74—1)

To all whom it may concern:

Be it known that I, Jay J. Hatfield, a citizen of the United States, residing at city of Asbury Park, in the county of Monmouth, and State of New Jersey, have invented a new, original, and ornamental Design for a Magnetic Desk Name Plate, of which the following is a specification, reference being had to the accompanying drawing forming part thereof.

The figure is a top perspective view of a magnetic desk name plate, showing my new design. The name shown in broken lines being merely representative of the name of the owner.

I claim:

The ornamental design for a magnetic desk name plate, as shown and described.

JAY J. HATFIELD.
